UNITED STATES PATENT OFFICE.

JOHN THOMPSON, OF PHILADELPHIA, PENNSYLVANIA.

DESIGN FOR A TIRE TREAD.

Application filed May 1, 1925. Serial No. 13,275. Term of patent 7 years.

To all whom it may concern:

Be it known that I, JOHN THOMPSON, a citizen of the United States, residing at Philadelphia, in the county of Philadelphia and State of Pennsylvania, have invented a new, original, and ornamental Design for Tire Tread, of which the following is a specification, reference being had to the accompanying drawing, forming a part thereof.

The figure is a sectional perspective view of a tire showing my new tread design.

I claim:

The ornamental design for a tire tread, as shown.

JOHN THOMPSON.
